UNITED STATES PATENT OFFICE.

DEXTER W. PARKER, OF MERIDEN, CONNECTICUT, ASSIGNOR TO THE CHARLES PARKER COMPANY, OF SAME PLACE.

LAMP.

SPECIFICATION forming part of Letters Patent No. 401,583, dated April 16, 1889.

Application filed April 24, 1888. Serial No. 271,712. (No model.)

To all whom it may concern:

Be it known that I, DEXTER W. PARKER, of Meriden, in the county of New Haven and State of Connecticut, have invented a new and useful Improvement in Lamps; and I do hereby declare that the following is a full, clear, and exact description thereof, reference being had to the accompanying drawings, making part of this application.

10 My invention relates to that kind of lamp in which a tubular flame is produced, and that is generally known as an "Argand-burner" lamp; and it consists in certain novel features of construction, which will be 15 found hereinafter fully described, and which are made the subject of the claims of this specification.

To enable those skilled in the art to which my invention relates to understand and practice it, I will now proceed to more fully describe the latter, referring by letters to the accompanying drawings, which form part of this specification, and in which I have shown an Argand-burner lamp embodying the several features of my said invention carried out 25 in those forms in which I have so far successfully practiced the said features of improvement, though some or all of them might be carried into effect under modifications of what 30 I have herein shown and described.

In the drawings, Figure 1 is a side elevation of an Argand-burner kerosene-lamp made according to my invention. Fig. 2 is a vertical section of the same, taken at the line $x-x$ of Fig. 1. Fig. 3 is a perspective of the combined perforated air-distributer and flame-spreader detached, and Fig. 4 is a detail horizontal section at the line $y-y$ of Fig. 2.

In the several figures the same part will 40 be found everywhere designated by the same letter of reference, and wherever any arrows occur they indicate the directions of movement of the air currents or jets which are supplied to produce the proper combustion 45 in the flame of the burner.

A is the reservoir or oil-receptacle, made, in the case shown, of sheet metal and formed or provided with a suitable foot or base, L, having perforations l therein of sufficient capacity to afford an ample supply of air to

constitute the interior air-draft of the Argand burner. This reservoir or fount A is formed or provided (in about the usual manner) with an inner air-supplying wick-tube, D, which tube is formed with an annular or circumferential inwardly-projecting bead at N, the function and effect of which will be presently explained; and the said reservoir A also has the usual hole and screw-stopper at M for the purpose of feeding or supplying it with oil, and another smaller aperture, preferably provided with a short tubular guideway, f , as shown, (see Fig. 2) for the accommodation of the vertical rod or hand-piece of a wick-raiser, F.

Arranged telescopically within the upper central opening of the reservoir is the lower end or portion of a cylindrical device, which is formed with an annular bead at a , that rests (or is seated) on the upper edge of the part b of said reservoir, and which is foraminous at e , and the upper end of which is provided with an ordinary chimney-gallery, g . This cylindrical device is also provided with the usual outer wick-tube, h , the upper end of which lies in the same plane with the upper end of the inner wick-tube, D, all as clearly shown.

m is a perforated cylinder arranged to fit easily within the foraminous portion e of the cylindrical device before mentioned, and said cylinder m has its perforations so arranged and of such size that by the turning slightly of said cylinder on its imaginary axis its holes may be thrown into and out of register with those of the perforated portion e of the device, within which said adjustable cylinder m is fitted.

K is a protruding handle or finger-bar projecting outwardly from the upper portion of m , (through a suitable slot in the base of the chimney-gallery,) by means of which the movable cylinder m may be turned in one or the other direction, as may be required.

Surrounding the inner wick-tube, D, and with its upper portion confined between the exterior of said tube and the interior of the outer wick-tube, h , is arranged an ordinary tubular wick, G, in the manner clearly shown, and said wick is held vertically in place while

the lamp is burning, and is raised and lowered, for the usual purposes, by means which I will now describe.

E is a short metallic tube, which has formed in it one or more (preferably three) inwardly-springing tongues, H, each of which may be formed with engaging-points, as at o, to stick into the wick G, if it be found expedient to so construct them.

- 10 C is a foraminous thimble or a perforated air-distributer that is removably but not adjustably combined with the upper portion of the inner wick-tube, D, in such manner, as shown, that all the supply-air or air-currents 15 entering at the perforated base of the lamp and ascending within the tube D must pass through the apertures of said device C, and, escaping thence, act upon the inner wall or surface of the tubular flame of the burner.
- 20 On top of this perforated thimble C is located a spreader or button, c, which may be rigidly secured to the upper end of C, as shown, and that performs the well-known function of spreading the tubular flame at a level slightly 25 above that at which the flame starts out from the upper end of the wick G. This air-distributer C is preferably made frustuminal in shape, (see Figs. 2 and 4,) and it is essential that the holes therein be made of considera- 30 bly greater capacity at the vicinity of the lower portion of the distributer than near the upper part, in order that a more ample supply of air be afforded to the lower portion and more stable portion of the tubu- 35 lar flame than to the upper and weaker portion of the latter. In other words, it is im- portant in the construction of this air-dis- tributer (no matter what its exact contour or shape in vertical section may be) to make it 40 capable, either by a variation in the sizes of its apertures or in the number of them at the lower part as compared with those at the upper portion, of supplying jets of air of more volume to the lower portion of the inner wall 45 of the flame than to the upper portion of the latter. In the case shown the device C, with its spreader c, is held in place in exactly the proper relationship to the upper end of the burner proper by means of a series of elastic 50 or spring-like catches, I, at the base of the perforated thimble, engaging with the inwardly-projecting circumferential bead N of the inner wick-tube; but some other means might of course be employed to effect the 55 return in place of said thimble, it being es- sential only that it be securely held in place against any accidental displacement or move- ment in any direction, and be at the same time readily removable by design.
- 60 It will be understood that by the use of the foraminous distributer C, arranged and oper- ating substantially as herein shown and de- scribed, numerous air-jets are projected laterally against the inner wall of the tubular flame, besides the ample ascending and tubu- 65 lar air-current which naturally rises nearly coincident with and in impingement against

the inner wall of the inner wick-tube, D, from a point or level nearly coincident with the external base portion of the distributer C; and 70 it will be seen that by constructing the distributer C in the manner described, so that air-jets of greater volume and force will escape at and near to the lower portion or root of the flame, a greater degree of perfection of 75 combustion is attained with more steadi- ness in the flame, and that consequently the illuminating capacity of the burner is im- 80 proved. The tendency of the laterally escap- ing or projected currents from the upper por- tion of the distributer (see the arrows at Fig. 2) is to promote perfect combustion at the locality of the upper inner portion of the tu- bular flame, especially where it is spread by the periphery of the button or disk c, and by 85 this intensifying the heat at this locality not only is the flame rendered more luminous, but the metallic spreader c is made to assist rather than to retard the illuminative capac- 90 ity of the flame itself.

By the use of the adjustable or register- 95 like wind-guard or air-distributer for supply- ing air to the interior of the chimney and the exterior of the flame this supply of air to the burner may be perfectly regulated or varied, 100 according to all the surrounding circumstances and variable conditions under which the flame may be created. The capacity of this perforated wind-guard or foraminous air-regu- 105 lator should be such, of course, that when the holes of the inner movable cylinder, m, are in perfect register with those of the outer sta- 110 tionary cylinder, e, a superabundance of air will be supplied to the outer wall of the tubular flame, so that under any changed 115 conditions or circumstances, should the sup- 120 ply of air to the exterior of the flame appear to more than counterbalance or properly com- 125 port with the supply to the interior of the flame, the exterior supply may be reduced to 130 any desired extent by simply taking hold of the hand-piece K and slightly turning or ad- justing the movable device m. By these means and in the manner referred to, just the proper relationship between the quantity 135 of air supplied to the exterior of the flame and the supply-currents to the interior of the flame may be established and maintained under various conditions with reference to the character of the wick and the oil-supply 140 and other conditions and circumstances sur- 145 rounding the use of the burner.

If deemed expedient, a register-like or ad- 150 justable device may be employed in connec- 155 tion with the perforated base of the lamp similar in construction and mode of operation to the adjustable distributer used for the sup- 160 ply to the outside of the flame, for the pur- 165 pose of varying, as circumstances may re- 170 quire, the quantity of air admitted to the in- 175 terior of the tube D, and, secondly, the amount of air supplied to the inner wall of the tu- 180 bular flame.

Of course the main advantages of my novel

construction of lamp may be attained whether the form of the distributor C be that shown or some other; but under any modification as to form the shape should be such as to permit a free and ample egress of air through the perforated distributor C at the vicinity of its base or lower portion, so that not only will the upper portion of the inner wick-tube be kept at the proper or desirable temperature, but also so that an ascending tubular supply of air, so to speak, will be supplied to the root of the flame, which column of air, as before mentioned, is supplemented or augmented from the point where the oxygen is all consumed by the process of combustion by the finely and laterally projected jets of air, which are supplied from the upper portion of the perforated thimble C.

The button or spreader c might of course be adjustably combined with the upper end of the thimble C, or it might be supported independently of said thimble without changing in any material way the principle of construction and mode of operation of the group of devices shown and described, so long as said button or spreader occupies the proper relationship to the upper end of the burner and properly performs its function of deflecting the flame, and also preventing the escape upwardly of the jets of air which are laterally projected from the extreme upper portion of the perforated thimble C.

Having now so fully explained the construction and operation of my improved lamp as to enable those skilled in the art to understand and practice my invention, and wishing it to be understood that whatever novel features may be contained in the wick-raising mechanism of my lamp are not claimed in this application, because it is contemplated to make claims thereon in a separate or divisional application, what I claim in this case

as new, and desire to secure by Letters Patent, is—

1. In combination with the usual inner and outer wick-tubes of an Argand-burner lamp and a suitable wind-guard or air-distributer for supplying the outer draft, the non-adjustable but removable perforated air-distributer, (for supplying the inner draft to the tubular flame,) and means which operate to hold said air-distributer and the inner wick-tube in a given relative position against casual misplacement, all substantially in the manner and for the purposes hereinbefore set forth. 45

2. In combination with the inner and outer wick-tubes of an Argand burner and suitable means for supplying air to the outside tubular flame, a removable perforated air-distributer having its lower portion arranged interiorly of the upper portion of the inner wick-tube, an annular seat or support, N, formed in said inner wick-tube, and spring-catches at the base of said perforated air-distributer, which engage with said annular seat N, all 50 55 in the manner and for the purposes hereinbefore described.

3. The combination, with the inner and outer wick-tubes of an Argand burner and a suitable air-distributer for supplying the outer draft to the flame, of a removable perforated air-distributer for supplying the inner draft, having its perforations graduated either as to size or as to number, so as to supply the air in greater volume at the vicinity of its base 70 75 than at the vicinity of its upper portion, substantially in the manner and for the purpose hereinbefore set forth.

In witness whereof I have hereunto set my hand this 14th day of April, 1888.

DEXTER W. PARKER.

In presence of—

RALPH A. PALMER,
WILLIAM T. RIGHTMYER.
